United States Patent Office.

MILTON V. NOBLES, OF ELMIRA, NEW YORK.

Letters Patent No. 63,082, dated March 19, 1867.

IMPROVED BOAT-DETACHING TACKLE.

The Schedule referred to in these Letters Patent and making part of the same.

TO ALL WHOM IT MAY CONCERN:

Be it known that I, MILTON V. NOBLES, of Elmira, in the county of Chemung, and State of New York, have invented certain new and useful improvements in Boat-Detaching Apparatus; and I do hereby declare the following to be a full, clear, and exact description of the same, reference being had to the accompanying drawings, making a part of this specification, in which—

Figure 1 represents a top plan of a life or other boat, with the disconnecting apparatus in place.

Figure 2 represents a vertical longitudinal section through the boat, and showing a side elevation of the disconnecting apparatus.

Figure 3 represents one of the tripping-rods for operating the let-go.

Similar letters of reference where they occur in the separate figures denote like parts in all the drawings.

The object and purpose of this invention are to avail myself of the central detaching devices, whilst I also steady the boat laterally and prevent it from tipping when hastily let go or unevenly loaded; and my invention consists in centrally suspending the boat, but bracing it laterally to prevent tipping or rocking by uneven loading, and in either leaving the brace with the bolt or letting it go with the davit-blocks or other lowering tackle.

To enable others skilled in the art to make and use my invention, I will proceed to describe the same, with reference to the drawings.

On the right of fig. 1 I have represented a bar or brace *a*, which, when the boat is disconnected from the lowering tackle, goes with the tackle. This bar lies between studs or pins 1-2 and 3-4, arranged on the sides of the boat, and from each of its ends and from its centre metal rods or straps *b* extend toward each other, and terminate in an eye, *c*, into which the lowering tackle is hitched. From the centre of this bar *a* a suspension-rod, *d*, fig. 3, extends downward into a tube, *e*, and is guided and held therein by the enlarged portion *f* into a hole in which the rod *g* shoots after passing through the tube. The pins in this case keep the bar in place, and the bar serves to prevent the boat from tipping; but when the rod or bolt *g* is withdrawn from the hole in the piece *f*, then the whole brace is disconnected from the boat and goes with the lowering tackle.

On the right of fig. 1 I have shown a modification of that just above described, wherein the brace is hinged to the boat at *i*, and has a central suspension-rod, *d'*, that moves through a collar or ring, *h*, on the brace; and to the top of this rod is hinged a hook or bent lever, *n*, the point of which catches and holds in the ring or collar *h*, but when the rod or bolt *g* is withdrawn the suspension-rod has no rigid connection with the boat, the latter drops and its first movement slips the ring or collar *h* from the point of the hook, which allows it to fly and detach from the lowering tackle. The two rods or bolts *g g* may be simultaneously withdrawn by the pivoted lever *m*, to which they are connected at uniform distances each side of its point of vibration, and may be moved in contact with rollers to remove friction caused by the weight upon them.

Having thus fully described my invention, what I claim therein as new, and desire to secure by Letters Patent, is—

The combination of the detaching apparatus with the brace, and with the central suspension of the boat, as and for the purpose herein described and represented.

M. V. NOBLES.
